UNITED STATES PATENT OFFICE.

JOHN McNULTY, OF GULFPORT, MISSISSIPPI.

FOUL-AIR REMOVER.

Application filed August 31, 1921. Serial No. 497,205.

To all whom it may concern:

Be it known that I, JOHN McNULTY, a citizen of the United States, residing at Gulfport, in the county of Harrison and State of Mississippi, have invented certain new and useful Improvements in Foul-Air Removers, of which the following is a specification.

My invention relates to an apparatus designed for use in school rooms, assembly halls, and other such gathering places, for the purpose of maintaining an even heat and distribution of air throughout the room, and at the same time provide a positive means for drawing off the foul air without causing any undue draft, or undue acceleration of the rate at which the foul air is carried out of the room.

The primary object of the invention is to provide a device of this character which is simple, inexpensive, durable and efficient in operation, and which is readily applicable to any of the heating elements as now used in school rooms, assembly halls and public meeting places.

Another object of the invention is to provide a foul air remover as described in which means are provided for adjusting the rate at which the foul air is carried off, whereby the device may be adapted to different sizes of stoves to provide a uniform rate of distribution in the ventilating system.

A further object of the invention is to provide in a device of this character, means for drawing off foul air, so constructed and arranged that the medium through which the air is fed away from the room is acted upon by the heated air within the room and not by direct radiation from the stove or chimney flue, such as in use at the present time.

With these and such other objects in view as will be apparent from the description, my invention resides in the novel construction, combination and arrangement of parts hereinafter described and claimed, and illustrated in the accompanying drawing, in which—

Figure 1 is an elevation showing my invention in assembled position as applied to the heating stove of the type ordinarily employed in school rooms;

Figure 2, a horizontal section taken on the line 2—2 of Figure 1;

Figure 3 is a vertical section through the

foul air duct with an additional pipe section interposed between the foul air duct and the elbow 10.

Figure 4, a horizontal section on the line 4—4 of Figure 3.

My invention comprises the combination with a heating stove, which may be of any approved type, as indicated at 1, in this instance, of the circular form, of a casing 2, formed of sheet metal and adapted to surround the stove in concentric relation to provide an effectual screen entirely around the stove. The casing 2 may be constructed of a plurality of vertical sections secured to upper and lower supporting rings 3 and 4, respectively, to which the casing is attached in any suitable manner, and it is immaterial to the present invention as to the specific structural details of the casing proper other than it be of sufficient dimensions to extend entirely around the stove to provide an unobstructed air passageway around the stove. The casing is provided with a door 5 and the top of the casing is open and spaced above the top of the stove 1 as clearly indicated in Figure 1.

Fresh air is admitted to the air space around the stove, this space being designated as at 6, by means of a conduit 7, which, in this instance, comprises ordinary metal piping attached to the casing 2 at the lower portion thereof, to permit the ready entry of the air below the bottom of the heating stove, the relative position of the parts being illustrated in Figure 1. The stove 1 is provided with the ordinary outlet pipe 8, which is extended above the top of casing 2. It is obvious that with the construction described, fresh air will be drawn in at the bottom of the stove through pipe 7 into the casing 2, and will be heated in its circulation around the stove, passing out over the top of the casing and into the room. As a means of withdrawing the foul air which collects at the bottom of the room, due to the circulation, I provide air ducts 9, mounted on the casing at diametrically opposite points and extending vertically thereon from a point spaced above the top of the casing to within a short distance of the floor. These air ducts, as illustrated in Figure 4, comprise semi-cylindrical metal sections bolted or otherwise suitably secured to the walls of the casing, and are adapted to receive at their upper ends elbows 10 comprising pipe

sections of different diameter which are adapted to extend on an angle approximating 30° with the horizontal plane into a central vertical pipe section 11 of still larger diameter, which may be suitably connected to a flue extending through the roof for leading off the foul air, carried up through the air ducts 9 and elbows 10.

In the preferred form of my invention, I 10 provide a drum 12 secured on the lower end of pipe 11 below the junction of the elbows 10 therewith. Suitably secured to the drum 12 and extending therebeneath is a cone-shaped member 13 having an open bottom 15 and provided with circumferentially disposed perforations 14 adjacent the top. Elbows 10 and pipe 11, drum 12 and member 13 are disposed directly above the center of the top of the heating stove 1 and spaced 20 thereabove a sufficient distance so that the heated air arising from within the casing will circulate about these various members and impart a portion of heat thereto, which serves to set up a circulation within the 25 aforesaid pipes and air ducts 9, thereby causing the foul air to be drawn from the bottom of the room and carried off as described. Inasmuch as it is my intention to construct these casings and various parts of 30 uniform sizes it is desirable to make same adjustable to meet the conditions inherent in the use of various sizes of stoves, taking into account fuel employed as well as many other details. Accordingly, the drum 12 35 and elbows 10 may be raised or lowered relative to the top of the casing by the addition of pipe sections, as required, or by taking out a sufficient number of sections to provide for the proper spacing of these members 40 above the top of the casing and stove.

When it is found that too great a heat is set up by the stove and carried to the walls of the casing, which would greatly accelerate the upward flow of the foul air within 45 the air ducts 9, due to the fact that the rear walls of the ducts are formed by the casing, this undesirable condition may be overcome by insertion of spacing members 15 within the air ducts, which, owing to their construction and arrangement, will provide a rear wall for the ducts, which are spaced 50 away from the casing wall, and provide a vertical air passage 16 in each duct. These spacing members 15 comprise channeled 55 metal sections of approximately the same height as the duct, and adapted to be slid thereinto from the top, the elbows 10 having first been removed. The lower end of the section 15 is adapted to rest on a projection 60 17 which may be suitably formed on or otherwise attached to the casing and the upper end thereof is formed with an inwardly curved portion 18 having a portion thereof bent to form a bend 19 and a vertical lip 20, 65 the arrangement and disposition of these

elements being such that the bend 19 will be aligned with the wall of the casing 2 and spaced thereabove to provide an outlet for the air passage 16, the elbows 10 being then supported by the bends 19 and guided by 70 the lips 20.

It is obvious that this principle of construction may be applied to square casings adapted for use in connection with square heating stoves, and that the shape of the 75 parts may be varied to suit conditions, and, while I have described and illustrated certain preferred forms and details which enter into the construction and operation of the invention, I desire it to be expressly understood that it is not my intention to limit myself in any way to the specific details, but that any such may be used as will fall within the scope of the invention as claimed.

I claim:

1. A device of the character described, comprising a casing adapted to surround and enclose, in spaced relation, a heating element, means for supplying fresh air to the interior of said casing beneath the heating 90 element, and means for conveying the foul air, comprising a pipe disposed in spaced relation above said casing, conduits in connection with said pipe, said conduits being carried on the exterior sides of the casing 95 and extending thereabove to form supports for said foul air pipe, the top of said casing being open to permit of the heated air in the interior of the said casing circulating about said foul air pipe, whereby a circulation of foul air is set up within said conduits and pipe.

2. In a foul air remover, a casing adapted to surround a heating element in spaced relation therefrom, a fresh air inlet in said casing, the top of said casing being open to provide an outlet for air heated within the casing, foul air conduits carried by said casing, a portion of said conduits being disposed in the path of the heated air arising from the interior of the casing whereby circulation will be caused within said conduits for the removal of foul air, and adjustable pipe sections in said conduits whereby the rate of said circulation may be decreased or 110 accelerated as desired.

3. A device of the character described, comprising a cylindrical metal casing, adapted to surround a heating element, a fresh air intake pipe connected at the bottom of said casing, the top of said casing being open to provide for the escape of heated air, semi-cylindrical pipe sections secured to the exterior of said casing to form with said casing conduits extending entirely up the walls of the casing, the lower ends of said conduits being open and disposed adjacent the bottom of the casing, angled elbows carried by the upper ends of 120 said sections, and spaced above the top of 125 said sections, and spaced above the top of 130

said casing, and a vertical pipe section connected with said elbows, the bottom of said vertical pipe section being disposed in the path of the heated air in the interior of 5 the casing, whereby a circulation is caused within said conduits and pipe sections to draw the foul air into said conduits adjacent the bottom of the casing.

4. A device of the character described for 10 use in connection with a heating element provided with a chimney pipe, comprising a casing open at the top and adapted to enclose said heating element at the sides and bottom in spaced relation, and provided with 15 a fresh air inlet, a foul air conduit carried by said casing externally thereof, a foul air flue pipe disposed in spaced relation above the top of the casing in spaced relation to and independently of the heating element 20 chimney pipe, connection between said conduit and foul air flue pipe, said foul air flue pipe and connection being disposed in the path of heated fresh air arising from within the casing whereby the heated fresh 25 air will heat said foul air flue pipe to cause

a moderate circulation of foul air through said conduit, connection, and flue pipe.

5. In a foul air remover, a casing adapted to surround a heating element in spaced relation therefrom, a fresh air inlet in said 30 casing, the top of said casing being open to provide an outlet for air heated within the casing, foul air conduits carried by said casing, a pipe disposed in spaced relation above 35 said casing, elbows in connection with said conduits, and supporting said pipe above the center of the casing, a portion of said pipe extending below the joint of said elbows, and a flared member secured to said lower portion of the pipe whereby heated air arising 40 from the interior of the casing will be collected and brought in contact with the bottom of said pipe, said pipe being closed at the bottom and the adjacent portion of said flared member being provided with perforations to permit of the circulation of 45 heated air therethrough.

In testimony whereof I affix my signature.

JOHN McNULTY.
